UNITED STATES PATENT OFFICE.

HORATIO S. SEELY, OF SYRACUSE, NEW YORK, ADMINISTRATOR OF OBADIAH SEELY, DECEASED, ASSIGNOR TO E. C. STEARNS & CO., OF SAME PLACE.

DESIGN FOR A BICYCLE-STAND.

SPECIFICATION forming part of Design No. 27,072, dated May 18, 1897.

Application filed April 2, 1897. Serial No. 630,485. Term of patent 7 years.

To all whom it may concern:

Be it known that OBADIAH SEELY, deceased, late a citizen of the United States, residing at Syracuse, in the county of Onondaga and State 5 of New York, did invent and produce a new and original Design for Bicycle-Stands, of which the following is a specification, reference being had to the accompanying drawings, showing a part thereof.

10 The essential features of the design are a standard and a slender vertical shaft extending upwardly therefrom supporting two inclined arms, both of which terminate in curved ends or hooks. These arms are arranged in 15 the same plane and extend upwardly, one toward one side and one toward the other, substantially at right angles to each other.

10 The invention will be understood by reference to the accompanying drawings, in which 20 the same numerals of reference refer to the same parts in all the figures.

Figure I is a front elevation of the design. Fig. II is a side elevation thereof, seen from the right. Fig. III is a cross-section of the 25 shaft on line III III of Fig. I.

1 The standard, having legs 2 2 2, three in number, supporting the elongated vertical shaft 3, finished with ribs 4 4 4 on its edges. These ribs may be formed on both 30 the front and rear faces, as indicated in Fig. III, or on one face only. From the upper end of the shaft extend upwardly and toward the

right and left, respectively, arms 5 and 6, one longer than the other—the left arm 6, as here shown. The ends 7 7 of these arms are bent 35 outwardly and downwardly and finished with similar hooks 8 8.

The front of the stand, as shown in Fig. I, may be finished with a bent plate 9, of which the lower portion 10 fits rather closely to the 40 front surface of the shaft and the upper portion 11 is bent outwardly. To this plate 9 is attached a forked arm or extension 12, extending outwardly from the side of the shaft.

The design is simple and peculiar, from 45 which it harmonizes with bicycles which, sustained on such stands, are often displayed in shop-windows and other locations.

Having described the invention, what is claimed as new, and desired to be secured by 50 Letters Patent, is—

The design for a bicycle-stand, as herein shown and described.

In witness whereof I have hereunto set my hand, in the presence of two attesting witnesses, at Syracuse, in the county of Onondaga, in the State of New York, this 12th day of March, 1897.

HORATIO S. SEELY,
Administrator of the estate of Obadiah Seely.
